US0D1046051S

(12) United States Design Patent (10) Patent No.: US D1,046,051 S
(45) Date of Patent:  Oct. 8, 2024

(54) FOLDING TENT FRAME WITH CANTILEVERED ROOF

(71) Applicant: Wuyi Letu Leisure Products Co., Ltd., Jinhua (CN)

(72) Inventors: Xin Qiu, Jinhua (CN); Huakai Pan, Jinhua (CN); Xuanyin Tao, Jinhua (CN)

() Term: 15 Years

(21) Appl. No.: 35/516,200

(22) Filed: Jan. 13, 2023

(80) Hague Agreement Data

Int. Filing Date: Jan. 13, 2023

Int. Reg. No.: DM/226460

Int. Reg. Date: Jan. 13, 2023

Int. Reg. Pub. Date: Feb. 10, 2023

(51) LOC (14) Cl. 21-04

(52) U.S. Cl.

USPC D21/839
